CIRCUIT CONTROLLER

Edgar F. Hathaway, Wellesley, and Walter Bixby,
Dorchester, Mass.

Application October 25, 1934, Serial No. 749,938

11 Claims. (Cl. 200—47)

Our present invention relates to circuit making and breaking devices and more particularly aims to provide an improved circuit-controller or limit-switch adapted variably to determine the operating period of an electric motor in accordance with the movement of a driven part and/or predeterminedly and adjustably to limit the travel of electrically driven devices.

In the drawing illustrating by way of example one embodiment of our invention,

Fig. 1 is a plan view of a controller or switch and its housing, with the cover plate removed;

Fig. 2 is a cross-section, looking down, substantially on the line 2—2 of Fig. 1;

Fig. 3 is a cross-section substantially on the line 3—3 of Fig. 1, looking from right to left, and with the cover plate in position; and

Figs. 4 and 5 are sectional views, with outer parts omitted for clearness, looking from left to right upon the lines 4—4 and 5—5 of Fig. 3 respectively.

As illustrated, the device as a whole is compactly arranged and is adapted for ready mounting in operative position at a desired point of use. The switch mechanism accordingly is contained in a suitable box or housing 6 including a rear wall 7 and enclosing side walls 8 together with a removable cover plate 9, Fig. 3. Attaching or mounting means such as the feet 9^a may be provided on the housing.

In the form shown the switch is associated with a rotary part or driven element 10. The latter may be an integral part of or an extension of the rotor of an electric motor, or may be any relatively driven element in a train of mechanism associated with or driven by an electric motor whose operating period is to be controlled, or it may be driven from a source independent of the circuit or circuits to be controlled.

This rotary driven element 10, hereinafter referred to as the shaft, projects into the housing through a suitable bearing 11 on the rear wall, and in the illustrated embodiment is also journaled at its front end in a bearing 12 on the cover plate. Between said bearings there is keyed on the shaft 10 an eccentric 13 surrounding which is a bushing 14, preferably of the so-called oilless type. Associated with the shaft and its eccentric are one or more sets or units of operating parts, depending on the number of circuits to be controlled. In the present instance, two such sets of elements are illustrated. They are shown as oppositely disposed, but otherwise may be duplicates of each other, one set accordingly being designated by the use of an exponent character "a" affixed to the same reference numeral used for the corresponding part of the other set.

On the eccentric bushing 14, loosely, are oppositely disposed gears 15, 15^a, each having projecting at its outer face a pair of diametrically

opposite pins 16. These pins are received in correspondingly arranged radial slots 17 in plates or cross heads 18, 18^a forming elements of coupling means in the nature of an Oldham coupling. The plates 18, 18^a have two other opposed radial slots 19, spaced ninety degrees from the first slots and receiving pins 20, 20^a on cams 21, 21^a loosely mounted on the shaft 10.

Surrounding each of the gears 15, 15^a is a ring gear 22, 22^a having an internal series of teeth 10 23, 23^a and an external tooth series 24, 24^a. These ring gears are held in place, laterally, between the adjacent plate 18 and a spacer 25 positioned between the gears 15, 15^a and loose on the hubs of the latter. The ring gears 22, 22^a are also 15 held in position, in their respective planes, by circumferential positioning shoes or lugs 26, 26^a, engaging the outer faces of a plurality of teeth of the external series of each of the ring gears, at angularly spaced points about the latter, and 20 permitting them to be turned for adjusting purposes when desired. In the illustrated example a third positioning element or shoe 27 is seen at the lower side wall of the housing, Figs. 1, 3 and 4. The ring gears are held normally stationary, 25 each by worm 40, 40^a, to be referred to later.

Each of the cam members 21, 21^a has a raised portion 28, 28^a for cooperation with cam rolls 29, 29^a mounted in yokes 30, 30^a on spring contact strips 31, 31^a. The latter are supported at one of 30 their ends on a bracket 32 on an insulating strip 33 carried by a wall of the switch box or housing 6. At the opposite or free ends of the spring strips 31, 31^a are the movable contact points 35, 35^a, Figs. 1 and 2, adapted to make and break 35 contact with underlying points 36, 36^a carried by contact brackets 37, 37^a on the insulating strip 33 or otherwise mounted on but insulated from the switch box.

The two pairs of contact points 35, 36 and 35^a, 36^a are adapted to be placed in and to control the making or breaking of a like number of circuits. The two circuits may have one common lead 38 connected to the bracket 32 and through it to the contact strip 31, the other strip 31^a 45 being insulated from the bracket, as indicated at 32^a. A removable connector 34 and binding posts 34^a may be supplied for cross-connecting the two strips 31 and 31^a with the common lead 38. Or two wholly independent circuits may be accommodated, by removing the connector 34 and connecting two separate leads one to the bracket 32 as illustrated (or to the binding post 34^a for the strip 31) and the other to the binding post 34^a for the strip 31^a. The switch as illustrated is 55 particularly adapted for controlling the forward and reverse circuits of an electric motor, to determine its operating period in each direction.

Referring more particularly to Fig. 4, it will be seen that the gear 15 has a pitch diameter less 60

- than that of the internal tooth series 23 of the surrounding ring gear 22. The number of teeth upon the gear 15 is also less than the number in said surrounding internal series. In the illustrated example the gear 15 has thirty-four teeth, of twenty-four pitch, while the surrounding internal series 23 contains thirty-six teeth, of similar pitch, the two series being adapted to mesh in the manner illustrated.
- 18 As before noted, the ring gear 15 normally is held stationary, by the worm 40. Assuming now that the shaft 10 is rotated clockwise, in the direction of the inner arrow on Fig. 4, the eccentric 13 is bodily revolved or gyrated in the same direction. The gear 15 at such time is caused to rotate on its own axis, around the center of the eccentric 13, but in a direction reverse to that of the eccentric movement, due to the fact that the ring gear 22 is held stationary while
- 19 the gear 15 engages it at progressively shifting points. This reverse rotation of the gear 15 is at a substantially reduced rate as compared with that of the shaft 10, the ratio illustrated being approximately one to seventeen. This rotary motion of the gear 15 is communicated through the pin and slotted-plate coupling means 16 to 28, and at the same rate, to the cam 21. Engagement of the raised portion 28 of the cam beneath the corresponding cam roll 29 raises the spring contact strip 31 and breaks the circuit between the corresponding movable and fixed contact points 35, 36. It will be understood that the operation in connection with the other gear set, cam, roll and contact points is similar.
- 20 In accordance with our invention, means is provided for angularly varying the position of the cams 15, 15^a with respect to their point of engagement with the cam rolls and also herein with respect to the shaft 10, and said means herein may be operated at any time, either while the shaft 10 is in motion or while it is stationary. For this purpose each of the ring gears 22 and 22^a has an external series of teeth 24 previously mentioned. These teeth may be variously proportioned, there being fifty four teeth, of twenty-four pitch in the example as illustrated. Each ring gear has in mesh with its external teeth one of the worms 40, 40^a respectively, referred to before in connection with their function of normally keeping the ring gears stationary. These worms are located at any convenient point about the gears. They are supported on adjusting shafts 41, 41^a projecting outwardly through bearings 42, 42^a in a wall of the housing, and are held in place, axially, as by collars 43, 43^a. Outside the housing, the adjusting shafts have manipulating portions 44, 44^a which may be provided with knurled heads 45, 45^a for convenience in turning them to effect a desired adjustment. Spring lock washers 47, 47^a or other retaining means such as a ball detent may be provided for holding the heads or knobs 45, 45^a at the desired setting.
- It will be seen that by turning a worm 40 or 40^a, in one or the opposite direction, a corresponding rotation of the associated ring gear 22 or 22^a is effected, whereby the cooperating gear 15, 15^a is rotated on its own axis, in a corresponding direction and to a proportionate extent. This angular variation in position is communicated in like measure to the corresponding cam 21 or 21^a. Thus, depending merely on the extent to which a worm is turned, the point of engagement of the raised portion 28 or 28^a of the corresponding cam with its roll, and hence the time of interruption of the circuit controlled thereby, may be

varied at will. The adjustment or variation may be through any desired increment however great or small, including extremely fine incremental adjustments, in either direction and at any time irrespective of the operative status of the shaft 10 and the controlled motor.

If desired, an index and scale calibrated in any convenient units may be provided in association with the adjusting members 44, 44^a, as indicated at 46, 46^a. Also it is noted that by making the same adjustment of both control units, through turning the adjusting members 44, 44^a to the same extent, either in the same or in opposite directions, the relative position of the two cams 21 and 21^a may be kept the same, but by making different adjustments through the respective adjusting members the two contact-interrupting cams may be differentially adjusted.

It will be apparent that our circuit controller is of wide application in connection with electric motors or parts driven by them. As one general example we mention an instance in which a sheet, web or strip is normally stored in rolled condition upon a drum or beam, from which it is to be unreled or run out a desired distance and subsequently returned. By the use of the switch or controller of our invention, in the plural form illustrated, one set of contacts may be employed to predetermine the extent of outward movement of the strip or the like, and the other set to limit and determine its return movement. The limits of both movements may be accurately varied and adjusted to any desired extent, either while the movement is in progress or during a stationary condition of the parts, as desired. Obviously the switch may be employed in single-circuit form, or any plurality of circuits may be controlled, in accordance with the number of cam and eccentric operating units supplied. The plural-circuit forms are not limited to the use of a common eccentric, or eccentricities of the same size or position. As previously indicated, the driven element or shaft 10 may be a part of or driven from a motor whose circuit is controlled by the switch, or it may be independently actuated, our switch being adapted to make or break any circuit in conformity with the extent of rotation or number of rotations of any rotary element and hence at time intervals proportionate to the speed of the rotary element, the setting of the switch with respect to the position of make or break being universally adjustable to any desired extent and irrespective of the operative status of the rotary element.

Our invention is not limited to the particular embodiment thereof illustrated and described herein, its scope being set forth in the following claims.

We claim:

1. A variable circuit-controlling switch comprising, in combination, a switch housing, a rotary driven element therein, an eccentric fast on said element, an inner gear rotatably mounted on the eccentric, a ring gear surrounding said gear and having an internal series of teeth engageable with said inner gear and also having an external series of teeth, positioning means for the ring gear, a worm meshing with said external teeth of the ring gear to hold it stationary or adjustably to turn it, a movable contact element in the circuit to be controlled, a rotary cam adapted to control said contact to make or break the circuit, positive coupling means between the inner gear and said cam, and adjusting means to turn

said worm thereby to vary the contact-controlling position of the cam.

2. A limiting circuit-controller for electric motors and electrically-operated devices, comprising, in combination, a driven shaft, an eccentric fast on the shaft, a gear rotatable on and bodily movable with the eccentric, means compelling the gear to rotate reversely on its own axis during its bodily movement with the eccentric, a cam loose on the shaft, positive drive connections between the gear and the cam, a movable contact operatively controlled by the cam, and adjusting means operable upon the gear thereby to vary the position of the cam.

3. A limiting circuit-controller for electric motors and electrically-operated devices, comprising, in combination with a rotary driven element, contacts including a movable contact through which a circuit may be made or broken, a rotary cam for operating the movable contact, said cam being loosely supported on the driven element, driving connections between the driven element and the cam, including an eccentric on the driven element, a rotary member on the eccentric and positive coupling means between said member and the cam, and means associated with said rotary member for varying the angular position of the cam while the parts are either in operation or at rest, thereby to advance or retard the operation of the movable contact.

4. A limiting circuit-controller for electric motors and electrically-operated devices, comprising, in combination, a rotary driven element, a rotary cam loose on the driven element, drive connections between the driven element and the cam for reversely rotating the latter from the former at a uniform but substantially reduced rate, electric contact means for actuation by the cam, and adjusting means operable on said drive connections to vary the position of the cam with respect to its point of actuation of said contact means by increments of any desired extent.

5. A limiting circuit-controller for electric motors and electrically-operated devices, comprising, in combination, a rotary driven element, a cam proportionately rotated by said element, worm and gear means to vary the relative angular positions of said element and cam universally within a range of 360° and with the driven element in motion or at rest, and circuit making-and-breaking means controlled by the cam.

6. A variable circuit-controlling switch comprising, in combination, a switch housing adapted for mounting at a point of use, a contact element movable to make or break the circuit to be controlled, a shaft rotatably supported in the housing and adapted to be driven from outside the latter, a rotary cam for actuating said contact element, positive drive connections including reduction gearing between the shaft and the cam, gear means associated with said drive connections for angularly adjusting the position of the shaft and the cam relatively to each other and irrespective of the operative status of the shaft, all said parts being operatively positioned within said housing, and operating means for said adjusting means operatively accessible outside the housing.

7. A variable circuit-controlling switch comprising, in combination, a switch housing adapted

for mounting at a point of use, a contact element movable to make or break the circuit to be controlled, a shaft rotatably supported in the housing and adapted to be driven from outside the latter, a rotary cam for actuating said contact element, positive drive connections including reduction gearing between the shaft and the cam, gear means associated with said drive connections for angularly adjusting the position of the shaft and the cam relatively to each other and irrespective of the operative status of the shaft, all said parts being operatively positioned within said housing, and said adjusting means being readily operable to effect said adjustment while the driven element is in normal motion.

8. A variable circuit-controlling switch comprising, in combination, a switch housing, a rotary driven element therein, an eccentric fast on said element, a gyratory gear rotatable on the eccentric, an internally toothed ring gear surrounding and meshing with the gyratory gear, supporting means for the ring gear, a movable contact element in the circuit to be controlled, a rotary cam to operate said contact, positive coupling means between the gyratory gear and said cam, and means engageable with the ring gear to hold it stationary or adjustably to turn it.

9. A variable circuit-controlling switch comprising, in combination, a switch housing, a rotary driven element therein, an eccentric fast on said element, a gyratory gear rotatable on the eccentric, an internally toothed ring gear surrounding and meshing with the gyratory gear, supporting means for the ring gear, a movable contact element in the circuit to be controlled, a rotary cam to operate said contact, positive coupling means between the gyratory gear and said cam, and means to hold the ring gear stationary thereby to effect rotation of the gyratory gear upon its own axis.

10. A limiting circuit-controller for electric motors and electrically-operated devices, comprising, in combination with a rotary element adapted to be driven in one and the opposite directions, a plurality of movable contacts controlling a like number of circuits, rotary cams, one for each contact, loosely supported on the driven element, eccentrics fast on the driven element, one for each cam, a rotary member on each eccentric, positive coupling means between each rotary member and the corresponding cam, and means for causing each rotary member to turn on its eccentric reversely to the direction in which the driven element is being driven thereby to rotate its cam to operate the corresponding contact, said cams being independently shiftable angularly with respect to the driven element to vary their contact operating times.

11. A variable circuit-controlling switch comprising, in combination, a switch housing, a rotary driven element therein, an eccentric fast on said element, a bearing on the eccentric, a gyratory member rotatable on said bearing, a rotary cam coaxial with and loosely carried by the driven element, a movable contact operable by the cam, means to cause said gyratory member to rotate on its own axis, and coupling means between the gyratory member and the cam whereby the latter is rotated in unison with the gyratory member.
